UNITED STATES PATENT OFFICE.

CHARLES E. McMANUS, OF NEW YORK, N. Y.

METHOD OF AND APPARATUS FOR MAKING COMPOSITION CORK SLABS.

Application filed June 27, 1923. Serial No. 648,110.

To all whom it may concern:

Be it known that I, CHARLES E. McMANUS, a citizen of the United States, residing at the borough of Manhattan, in the city, county, and State of New York, have invented certain new and useful Improvements in the Methods of and Apparatus for Making Composition Cork Slabs, of which the following is a specification, reference being had therein to the accompanying drawings, which form a part thereof.

My invention relates to a method of, and apparatus for, making composition cork slabs, and more particularly to a method and an apparatus by which such slabs will be made by substantially continuous operation during which the cork composition will be delivered to, and compacted within a mold, and while within the mold will be successively subjected to an elevated temperature, and a relatively lower temperature under conditions which will ensure substantial uniformity in the application of heat to the entire mass of composition cork and the adhesive or binder which is used as a thin coating for the cork granules.

Heretofore in the manufacture of cork slabs, my practice has been to deliver succeeding charges of cork granules having a thin coating of adhesive or binder, to within a suitably reinforced mold, each charge after delivery to the mold space being compacted by a mechanically actuated plunger or ram. Such molds are adapted for use in making slabs of fairly large superficial area, although the width of the mold space is of necessity limited to from one to two inches, to permit the absorption of heat by the entire mass with sufficient rapidity to make the binder active without subjecting the cork to an elevated temperature for a sufficient time interval to prove injurious to the cork itself, or to the adhesive or binder coating the cork granules which are positioned closely adjacent the walls of the mold.

The practice I have above referred to, while highly efficient as far as the production of cork slabs is concerned, is an intermittent process requiring the filling of one mold at a time, and the mounting and removal of this mold in the machine by hand, thus reducing the capacity output of each unit in a plant and increasing the labor required in producing the slabs. Furthermore, by reason of the size of the slabs pro-

duced and the necessity for great rigidity of the walls of the mold structure, the molds themselves are heavy and more or less difficult to handle, not only in relation to the packing unit, but in relation to the baker or vulcanizer. With such molds I have found it necessary to provide a knock-down structure at least to the extent of having one of the sides of the mold removable so as to permit the drawing of the cork slab through the side of the mold.

In order to secure the desired uniform density of the cork composition throughout the slabs, I have found it essential to pack these slabs by a compacting mechanism acting through one of the narrow edges of the mold as it is impossible to secure the necessary uniform distribution of the composition cork in granular form through a large area and avoid the formation of spots of greater density than elsewhere. Furthermore, if it were to be attempted to apply a compacting pressure throughout a large area, the power required would be so great, and the result so unsatisfactory, that the commercial production of cork slabs by such methods would be an impossibility.

By my present invention, I am enabled to produce cork slabs of the desired dimensions by a continuing operation, including the progressive filling of the molds with succeeding charges and the compaction of each charge after its delivery to the mold, the baking or vulcanizing of the contents of a mold, or of the binder or adhesive therein, for the purpose of firmly cementing the various cork granules together, the subsequent cooling of the molds and their contents to complete the setting of at least that portion of the adhesive which is adjacent the surface of the slab while in the mold, and the power ejection of such slabs from the mold at a time and under conditions permitting the immediate return of the molds to the packing mechanism, and thus minimize the number of molds necessary to keep the plant in continuous operation with a minimum investment for the operation of a plant of the desired capacity.

By the method of my invention, and with an apparatus for use in the practice thereof, I am enabled to employ rigid molds so constructed and arranged as to permit the introduction of succeeding charges of granular cork composition through one narrow

edge thereof, and the application of compacting pressure to each charge throughout the limited area defined by this narrow edge, with a resultant uniform compaction of the 5 charge and the production of a slab wherein the entire mass of composition cork will be of sufficiently uniform density.

In the ejection of the completed slab, dismemberment of the mold is not required, 10 particularly as the slab is ejected at a time when the condition of the cork composition is such as to offer a minimum resistance to movement of the slab due to any bonding action between the adhesive and the wall of 15 the mold. The entire mass of composition cork forming the slab, at the time that it is ejected from the mold, is sufficiently warm to permit the ready breaking of any slight bond which may exist between the surface 20 of the slab and the walls of the mold, notwithstanding that the temperature of the cork and its adhesive or binder is sufficiently low to ensure substantially complete setting of the latter, or a permanent bonding 25 together of the cork granules thereby.

The various molds, in order to facilitate their movement in relation to the various elements of the charging and packing mechanism, and through the baker or vulcanizer, 30 and their successive positioning in the proper relation to the ejecting mechanism, are mounted side by side upon wheeled carriages, but in spaced relation so as to not only maintain a fixed distance between the 35 molds to facilitate the action of the charging and compacting mechanism, but also to provide space between succeeding molds through which heated air may freely circulate so as to ensure the application of 40 heat about every portion of the outer surface of the mold and the desired rapidity in bringing the contents of the mold to a temperature to make the adhesive or binder active. At the same time such spaces between 45 and about the various molds will facilitate the radiation of heat, while the molds are passing through the low temperature zone after leaving the high temperature zone. To permit the handling of each vehicle as a 50 unit, I preferably close the bottom of each mold space by means of a plate carried by the vehicle itself, the movement of which plate in one direction will close the bottom of the molds upon the vehicle, and in 55 the other direction, will expose the open bottom of the mold to afford clearance for the passage of a completed slab, as it is ejected from the mold.

The invention consists primarily in a 60 method of making composition cork slabs consisting of intermittently moving a sequence of closely adjacent, spaced molds with relation to a packing mechanism adapted to progressively compact succeeding 65 charges of granular cork having a thin coat-

ing of an adhesive or binder, in alternate molds, said molds each having an angular mold space therein of relatively greater height than width and having a narrow top opening, delivering coated granular cork in 70 measured quantities through the narrow top opening of the molds intermediate those in which cork is being compacted, inserting a plug in the open top of each mold after the final charge of granular cork has been compacted therein, and thereafter successively passing the molds through a high temperature zone and a low temperature zone, to condition and set the thin coating of adhesive or binder upon the cork granules; and 75 in such other novel steps and practices, and in the novel features of construction of an apparatus for practicing said method, all as hereinafter set forth and described, and more particularly pointed out in the claims 80 hereto appended.

Referring to the drawings,

Fig. 1 is a side view of an apparatus embodying my invention condensed centrally thereof, and partly in vertical section; 90

Fig. 2 is a section on the line 2—2 of Fig. 1;

Fig. 3 is a section on the line 3—3 of Fig. 1;

Fig. 4 is a section on the line 4—4 of Fig. 1, showing the ejecting mechanism; and

Fig. 5 is a section on the line 5—5 of Fig. 4.

Like numerals refer to like parts throughout the several views.

In the practice of my method, I employ a sequence of molds mounted in spaced relation to each other upon a movable carrier. Each of these molds has a mold cavity rectangular in cross-section with a narrow top opening, the molds being of relatively greater length and height than width so as to permit the introduction of composition cork, and the compaction of such composition by pressure exerted, through the narrow top opening, so as to permit the gradual filling up of this slab by succeeding charges of composition cork. Each charge is compacted entirely independently of every other and to substantially the same extent, resulting in substantially uniform density throughout the entire mass. The compaction is effected by means of a single continuing pressure, and not by a tamping action, and consequently with a very small quantity of cork composition in each charge, the power required to compact each charge is not excessive although greater than is required for tamping. The carriage containing the molds is then advanced intermittently, or with a step by step movement, in relation to a packing mechanism, consisting of a sequence of packing members of gradually decreasing lengths in the direction of move- 130

ment of the carriage, so arranged as to act upon alternate molds, granular cork which has previously received a thin coating of adhesive or binder being introduced through the narrow top opening of the molds intermediate said compacting members while said members are operative in compacting the charges previously introduced to within the adjacent molds.

10 Of necessity the compaction of the last charge of composition cork delivered to the mold, will leave a space toward the top of the mold which is filled with a plug, the carriage with the molds thereon thereafter being successively passed through a high temperature zone and a low temperature zone, the high temperature zone serving to make the adhesive or binder active, and partially set the same, while the effect upon 15 the mold while passing through the low temperature zone, will be to complete any setting action by cooling the entire mass, and particularly the portions thereof adjacent the walls of the molds.

20 25 By mounting the molds in spaced relation, the heated air within the high temperature zone, and the cooling air in the succeeding low temperature zone, will act with substantial uniformity throughout the entire mass 30 of composition cork within the molds in a minimum of time, it being essential that the width of the molds, or the narrowest dimension of the mold cavity, shall range from one to two inches in order to afford a sufficiently thin mass thereof to facilitate the absorption of heat thereby within a period 35 of time sufficient to make the binder throughout the entire mass active, without injury to that portion thereof, or to the cork granules, 40 adjacent the walls of the mold.

45 After the molds and their contents have been cooled for a sufficient interval, the top plug and a closing means for the bottom of the molds are removed, and the molds, with the same movement by which they are fed with relation to the packing mechanism and through the high and the low temperature zones, are brought successively into relation to an ejecting mechanism by which pressure 50 is applied along one narrow edge of the slab formed within the molds to force this slab from within the molds, without the necessity of removing the molds from the carriage or opening same except as to the top and bottom thereof.

55 The slabs thus produced will be of substantially uniform density throughout, and will possess no voids or openings such as are found in natural cork, so that these slabs 60 may be readily sliced into thin strips from one-sixteenth of an inch upward in thickness, which strips are suitable for use in the manufacture of gaskets, sealing disks for bottle caps, and various other surfacing material 65 and various other articles of manufacture.

The temperature maintained in the high temperature zone may vary according to the adhesive or binder used, as will the duration of the passage of molds through this zone, a temperature as high as 400° to 500° F. being 70 permissible without likelihood of injury to the cork.

75 While packing the various charges by the application of pressure at the smallest cross-sectional area of the contents of the mold, will secure substantial uniformity in the density of the contents of the mold, equal distribution of the charge throughout the mold carrier is not always possible, nor is it always possible to have each charge identical 80 in bulk with every other charge. The tendency of the mass to expand, however, while passing through the high temperature zone, and while the adhesive or binder is plastic, will have the effect of developing such pressure internally of the mold as will cause a readjustment of the cork granules in the mass, and the equalization of pressure throughout the entire mass so as to correct 85 any irregularities in the mechanical compaction thereof, and bring the entire mass of the composition cork within the mold to substantially the same density.

90 The slab produced is highly resilient throughout, and may be readily sliced by 95 means of an ordinary band-knife slicing machine. The sheets produced possess a degree of flexibility equal to, or possibly even greater than, that of natural cork.

100 In the practice of my method or art, I employ an apparatus in which the charging and packing unit consists of a head 10 having a sequence of plungers 11, 12, 13, 14, 15 and 16, depending therefrom, each of these plungers having an oblong angular head 17 of slightly smaller dimensions than the open top of the various mold cavities. The plungers 11 to 16 inclusive are graduated in length, the plunger 16 being relatively shorter than the plunger 11, there being a 110 proportionate decrease in length from the plunger 11 to the plunger 16.

115 Mounted above the head 10 is a hopper 18 adapted to receive the composition cork to be delivered to the molds, this composition cork consisting of granular cork, the various granules of which have a thin coating of a suitable adhesive or binder responsive to heat for making the same active. Passing from adjacent said hopper 18 through the head 10 and intermediate the succeeding plungers 11 to 16 inclusive, are a sequence of chutes 19 through each of which a measured quantity of composition cork is delivered to a mold intermediate those upon which the various plungers are operative.

120 Intermediate the hopper 18 and the various chutes 19, I provide a suitable measuring device, which in the form of the invention shown consists of a slide 20 having 125

measuring pockets 21 therein adapted to be alternately brought into register with the openings 22 in the bottom of the hopper, and with the chutes 19 by a mechanism consisting, in the form of the invention shown, of a rock arm 23, one arm of which is acted upon by a cam 24 carried by, and movable with, the head 10.

Acting upon the head 10 are suitable counterweights 25 for assisting the actuating means for the head 10 during the movement of the plungers from the mold spaces.

The head 10 is actuated by means of two pairs of oppositely disposed crank wheels 26 and 27 having formed thereon intermeshing gears, which crank wheels are respectively connected by means of the rods 28 with the said head 10.

Extending below the various plungers 11 to 16 are oppositely disposed parallel tracks 29 upon which a sequence of carriages 30 are adapted to receive intermittent movement in any desired manner, as by hand. Said carriages 30 have permanently mounted thereon in spaced relation to each other a sequence of molds 31 spaced apart by means of the spaces 32, thus leaving air passages between succeeding molds. The top and the bottom of each mold is narrow and of much smaller cross-sectional area than the sides thereof, the top of each mold being adapted to be closed by a plug 33 after the mold has been completely charged with the composition cork, and the bottom thereof being closed by means of a movable plate 34 mounted upon each carriage. The bottom plate 34 may be actuated by a rack and gear mechanism 35, or in any other desired manner, the plate having spaced transverse bars adapted to be so positioned as to either completely close, or completely open, the bottom of each mold cavity. The tops of the molds upon each carriage are connected by a cap plate 36 having upwardly flared openings therein registering with the cavity of each mold space, to facilitate the introduction of the granular cork thereinto and the adjustment of the carriage by the various plunger heads 17, in the event of slight variation in the feeding movement of the carriage or carriages 30.

Above each of the tracks 29 are side guides 37 adapted to be engaged by antifriction rollers 38 mounted at spaced intervals in metal channels 39 connecting the various molds upon each carriage 30.

Adjacent the last or shortest plunger 16, is an oven 40 brought to the desired high temperature by means of gas burners 41, or any other suitable heating device, the tracks 29 extending through and beyond this oven so as to permit the completely packed molds to be successively passed therethrough and to be exposed for a sufficient period to complete the setting of the adhesive or binder,

to atmospheric air after leaving the oven. The oven 40 and the space about the track section beyond same constitute high, and relatively low, temperature zones through which the molds are successively passed. The use of side guides 37 above the portion of the tracks passing through the oven and through the low temperature zone beyond same, is not necessary, such guides primarily being provided for the purpose of firmly holding the various molds and the carriage supporting same in relation to the plungers of the packing mechanism.

After leaving the low temperature zone, the tracks 29 pass to an ejecting mechanism, by means of which the finally formed and completed slabs may be successively forced from the molds. This mechanism comprises a reciprocatory head 42 mounted upon suitable vertical guides 43 and carrying a plunger 44 having a rectangular head 45 of substantially the same configuration as, but slightly smaller than, the horizontal cross-sectional areas of the cavity of each mold. This plunger 44 is of substantially the same length as the plunger 11 so as to completely eject the formed slab from the mold.

The head 42 is acted upon by counterweights 46, and is reciprocated by means of the oppositely disposed crank wheels 47 connected by means of the rods 48 with said head 42. The throw of the wheels 47 and their angular speed is coincident with that of the wheels 26-27, and so timed as to impart to the ejecting plunger 44-45 a movement coinciding with that of the various packing plungers.

Adjacent the ejecting mechanism, I provide side guides 49 adapted to engage the rollers 38 upon the various molds.

As the last mold upon each carriage 30 has the cork slab ejected therefrom, said carriage may be restored to adjacent the packing member, and thus permit a substantially continuous operation of the machine with a minimum number of molds.

Below the ejecting plunger 44-45 is a chute 50 adapted to receive the slabs 51 as they leave the mold, and cause them to move out of the path of the next slab to be ejected by said plunger.

The operation of the herein described mechanism is substantially as follows:—

A sequence of carriages 30 are mounted upon the rails 29 and the bottom plate 34 so set as to close the bottoms of the molds upon each such carriage, the carriages then being advanced intermittently, or with a step by step movement, a distance equaling that between the vertical centers of succeeding molds. After each movement of the carriages, power is applied to the wheels 26 and 27, thus causing the head 10 to be brought downwardly so as to exert a continuing pressure upon the composition cork which

has previously been delivered to the molds which are immediately below each of the plungers 11 to 16.

While the plungers are in their elevated position, the cam 24 will have actuated the rock shaft 23 so as to position the openings in the slide 20 below the openings 22 in the bottom of the hopper 18, permitting cork to fill each of the pockets 21 in said slide 20. 5 Hence as the cam 24 descends with the head 10, the various pockets 21 will be brought into register with the chutes 19, the open lower ends of which will be in register with the open tops of the mold openings in advance of each plunger or ram 11 to 16 inclusive. 10 It will be understood that the cross-sectional dimensions of each of the pockets 21 and the chutes 19 is substantially the same as that of the molds, so that the cork 15 composition delivered to each mold with each actuation of the slide 20, will be substantially equally distributed throughout the mold space or cavity, and that this cork when delivered to the mold will be loose so 20 that the initial compressing action by the various plungers, upon their next actuation, will have a tendency to effect a lateral spreading of the composition cork in the event of slight inequality in the distribution 25 of the cork composition through the medium of the charging mechanism.

As a mold progresses through the packing mechanism so that it will be successively brought into operative relation to the plungers 11 to 16, the volume of cork composition delivered to same will be progressively increased, until each mold is completely filled, except to the extent of the space left as a result of the compaction of the final charge 40 by the plunger 16. It will also be observed that the stepped or graduated lengths of the plungers, will permit a number of molds to be simultaneously packed, the graduation of the length of the plungers compensating for 45 the progressively increased volume of cork composition present in each mold.

Before the various carriages are brought into the operative relation to the packing members, the bottom or plate 34 of each 50 carriage is actuated to bring the bars thereof below the mold space or cavity, thus closing the bottom of the mold, and after leaving the packing mechanism, a closure plug 33 is inserted in the open top of each mold.

55 After the molds have been packed and plugged in the manner described, the advancing movement will ultimately bring the carriages to within the baker or vulcanizer 40 through which they will progress for a sufficient period to cause the elevated temperature of this oven to properly condition the adhesive with which the cork granules are coated, so as to firmly bond these granules together. The oven 40 must be of a 65 length to afford the desired time interval

during which the molds with their contents are subjected to the high temperature, with the desired speed of the packing mechanism.

The spaced relation of the molds, as a result of the use of the spacers 32, will permit the heat of the oven to have access to all six surfaces of the mold, thus causing the rapid absorption of heat by the mold and its contents and limiting the time required to an extent to permit this heat to penetrate 75 the entire mass of composition cork without likelihood of injury to any portion thereof.

After leaving the high temperature zone of the baker or vulcanizer, the carriages with the molds thereon, will continue to 80 pass along the tracks 29, exposed to atmospheric air, which circulates entirely about each mold and thus gradually reduces the temperature thereof and of the contents, as the result of radiation of heat from all six 85 surfaces of the mold. As the carriages and the molds thereon approach the ejecting mechanism, an operator will remove the plug 33 from each mold, since by this time the composition of the cork slab within the mold will be sufficiently cooled to have caused slight shrinkage thereof as compared with its maximum expansion while within the high temperature zone. As each mold comes beneath the ejecting plunger 44-45, 90 power will be applied to this plunger by the operator, causing the head 42 of said plunger to descend, and thus force the slab from within the mold space while it and the walls of the mold are still slightly warm.

In order to permit the ejection of the slab, the mechanism 35 or other mechanism used for this purpose, is actuated to impart movement to the plate 34 to an extent to bring the space between the bars thereof beneath 100 the mold space so that the slab can pass through the bottom of the car upon the chute 50 when the plunger 44-45 descends.

The movements of the packing plungers and the ejecting plunger need not be rapid, 110 although they must be timed with relation to each other, since one mold will be completely packed with each descent of the head 10 requiring ejection of a slab from a mold with each stroke of the head 42. The guides 37 and 49 are used because the molds must be held against any possible tilting action while the packing plungers or the ejecting plungers are operative, it being immaterial whether the carriages have side sway or not 115 while passing through the high and low temperature zones.

After leaving the ejecting mechanism each mold is returned to adjacent the packing mechanism in any desired manner, thus permitting a continued operation of the machine with a small equipment of molds.

The mold space or cavity while limited as to its width to from one to two inches in order to secure an effective production of 130

cork composition slabs, may have any desired height or length, the height being largely determined by the number of compacting plungers used and the resistance encountered 5 by the ejecting mechanism. The use of the spacers 32 in addition to securing the desired spacing of the molds for the purposes heretofore described, also serve as braces for the side walls of the mold for imparting the desired rigidity thereto. The angle bars 39 and top plates 36 will serve to maintain the desired accurate alinement of the molds upon each carriage, the latter also serving, as stated, to correct any slight loss of alinement due to irregularities in the feeding movement of the carriages.

An apparatus embodying my invention need not be of high speed, since a single slab will cut into sheets having an aggregate surface of approximately one to two hundred square feet, and even with a machine of low capacity, a very high output of such sheets may be secured. With a multiple plunger machine and a substantially continuous operation as to the packing, baking or vulcanizing and ejection of the completed slab, the capacity may be very much increased as compared with a single plunger machine, with much less labor required for the same 30 gross output.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

40 1. A method of making composition cork slabs consisting of intermittently moving a sequence of closely adjacent, spaced molds with relation to a packing mechanism adapted to progressively compact succeeding charges of granular cork having a thin coating 45 of an adhesive or binder, in alternate molds, said molds each having an angular mold space therein of relatively greater height than width and having a narrow top opening, delivering coated granular cork in measured quantities through the narrow top opening of the molds intermediate those in which cork is being compacted, inserting a plug in the open top of each mold after the final charge of granular cork has been compacted therein, and thereafter successively passing the molds through a high temperature zone and a low temperature zone, to condition and set the thin coating of adhesive or binder upon the cork granules.

60 2. A method of making composition cork slabs consisting of intermittently moving a sequence of closely adjacent, spaced molds with relation to a packing mechanism adapted to progressively compact succeeding

charges of granular cork having a thin coating of an adhesive or binder, in alternate molds, said molds each having an angular mold space therein of relatively greater height than width and having a narrow top 70 opening, delivering coated granular cork in measured quantities through the narrow top opening of the molds intermediate those in which cork is being compacted, inserting a plug in the open top of each mold after the final charge of granular cork has been compacted therein, thereafter successively passing the molds through a high temperature zone and a low temperature zone, to condition and set the thin coating of adhesive or 80 binder upon the cork granules, and applying ejecting pressure to the narrow edge of the slab after the mold leaves the low temperature zone.

3. An apparatus for making composition cork slabs embodying therein a compacting mechanism, an oven, means whereby an elevated temperature may be maintained in said oven, an ejecting mechanism, a continuous track structure extending adjacent said compacting mechanism, through said oven and adjacent said ejecting mechanism, said ejecting mechanism being spaced away from said oven to form a low temperature zone, a carriage movable upon said track structure, a plurality of molds thereon, and removable means closing the bottom of said molds, whereby said molds may progressively have composition cork compacted therein, be subjected to an elevated temperature while passing through said oven, and to a cooling action while passing from said oven to said ejecting mechanism, and have the completely formed composition cork slabs ejected therefrom after leaving said low temperature zone.

4. An apparatus for making composition cork slabs embodying therein a sequence of plungers of progressively decreasing, graduated lengths, means imparting reciprocatory movement to said plungers, a hopper adapted to receive composition cork, means operating in synchronism with said plungers, whereby a measured quantity of composition cork is delivered from said hopper to molds in advance of each of said plungers, an oven, means whereby an elevated temperature may be maintained in said oven, an ejecting mechanism, a continuous track structure extending adjacent said plungers, through said oven and adjacent said ejecting mechanism, said ejecting mechanism being spaced away from said oven to form a low temperature zone, a carriage movable upon said track structure, a plurality of molds thereon, said molds being so positioned that when said plungers respectively are operative upon the composition cork within alternate molds, a charge of composition cork will be delivered to each

mold adjoining that upon which a mold adjoining that upon which the plunger is operative, and removable means closing the bottoms of said molds, whereby said molds may progressively have composition cork compacted therein, be subjected to an elevated temperature while passing through said oven, and to a cooling action while passing from said oven to said ejecting mechanism, and have the completely formed composition cork slabs successively ejected therefrom after leaving said low temperature zone.

5. An apparatus for making composition cork slabs embodying therein a track structure, a carriage movable upon same, a plurality of molds thereon each having a mold space of narrow width and having relatively greater length and height, removable means closing the bottoms of said molds respectively, a compacting mechanism including a plunger having a rectangular head of slightly lesser cross-sectional area than the cross-sectional area of the mold space, adjacent one portion of said track structure, means delivering a measured quantity of composition cork to the mold after each actuation of said plunger, an oven adjacent another portion of said track structure, means maintaining an elevated temperature within said oven, an ejecting mechanism adjacent another portion of said track structure and spaced away from said oven to form a low temperature zone, whereby said molds may progressively have composition cork compacted therein, be subjected to an elevated temperature while passing through said oven, and to a cooling action while passing from said oven to said ejecting mechanism, and have the completely formed composition cork slabs ejected therefrom after leaving said low temperature zone.

6. An apparatus for making composition cork slabs embodying therein a track structure, a carriage movable upon same, a plurality of molds thereon each having a mold space of narrow width and having relatively greater length and height, removable means closing the bottoms of said molds respectively, a sequence of plungers of progressively decreasing, graduated lengths, adjacent one portion of said track structure, and each having a rectangular head of slightly lesser cross-sectional area than the cross-sectional area of the mold space, means imparting reciprocatory movement to said plungers, a hopper adapted to receive composition cork, means operating in synchronism with said plungers, whereby a measured quantity of composition cork is delivered from said hopper to molds in advance of each of said plungers, said molds being so positioned that when said plungers respectively are operative upon the composition cork within alternate molds, a charge of composition cork will be delivered to each mold adjoining that upon which a plunger is operative, and removable means closing the bottoms of said molds whereby said molds may progressively have composition cork compacted therein, be subjected to an elevated temperature while passing through said oven, and to a cooling action while passing from said oven to said ejecting mechanism, and have the completely formed composition cork slabs successively ejected therefrom after leaving said low temperature zone.

8. An apparatus for making composition cork slabs embodying therein a sequence of plungers of progressively decreasing, graduated lengths, means imparting reciprocatory movement to said plungers, a hopper adapted to receive composition cork, and having a sequence of spaced openings in the bottom thereof, a slide mounted below said openings and having measuring pockets therein, chutes leading from adjacent said

slide to adjacent the open tops of molds positioned with relation to said plungers, operative connections between said plungers and said slide whereby with each actuation 5 of said plungers, the pockets in said slide will be alternately registered with the openings in the bottom of said hopper and said chutes to cause a measured quantity of composition cork to be delivered from said hopper to molds in advance of each of said plungers, an oven, means whereby an elevated temperature may be maintained in said oven, an ejecting mechanism, a continuous track structure extending adjacent said 10 plungers, through said oven and adjacent said ejecting mechanism, said ejecting mechanism being spaced away from said oven to form a low temperature zone, a carriage movable upon said track structure, a plurality of molds thereon, said molds being so positioned that when said plungers respectively are operative upon the composition cork within alternate molds, a charge of composition cork will be delivered to each 15 mold adjoining that upon which a plunger is operative, and removable means closing the bottoms of said molds, whereby said molds may progressively have composition cork compacted therein, be subjected to an 20 elevated temperature while passing through said oven, and to a cooling action while passing from said oven to said ejecting mechanism, and have the completely formed composition cork slabs successively ejected therefrom after leaving said low temperature 25 zone.

9. An apparatus for making composition cork slabs embodying therein a compacting mechanism, an oven, means whereby an elevated temperature may be maintained in said oven, an ejecting mechanism, a continuous track structure extending adjacent said compacting mechanism, through said oven and adjacent said ejecting mechanism, said 30 ejecting mechanism being spaced away from said oven to form a low temperature zone, a carriage movable upon said track structure, a plurality of molds thereon, guides upon opposite sides of said molds adjacent said compacting mechanism to prevent lateral movement of the molds while the plunger is operative in relation thereto, and removable means closing the bottoms of said molds, whereby said molds may progressively 35 have composition cork compacted therein, be subjected to an elevated temperature while passing through said oven, and to a cooling action while passing from said oven to said ejecting mechanism, and have the completely 40 formed composition cork slabs ejected therefrom after leaving said low temperature zone.

10. An apparatus for making composition cork slabs embodying therein a sequence of plungers of progressively decreasing, gradu- 45 ated lengths, a vertically reciprocatory head carrying all of said plungers, crank wheels, rods connecting said crank wheels to said head, whereby all of said plungers will be simultaneously reciprocated to the same extent, a hopper adapted to receive composition cork, and having a sequence of spaced openings in the bottom thereof, a slide mounted below said openings and having measuring pockets therein, chutes leading 50 from adjacent said slide to adjacent the open top of molds positioned with relation to said plungers, a rocking arm, one end of which is connected with said slide, a cam carried by said head and operative upon the other end of arm whereby with each actuation of said head, the pockets in said slide will be alternately registered with the openings in the bottom of said hopper and said chutes to cause a measured quantity of composition 55 cork to be delivered from said hopper to molds in advance of each of said plungers, an oven, means whereby an elevated temperature may be maintained in said oven, an ejecting mechanism, a continuous track 60 structure extending adjacent said plungers, through said oven and adjacent said ejecting mechanism, said ejecting mechanism being spaced away from said oven to form a low temperature zone, a carriage movable upon said track structure, a plurality of molds thereon, said molds being so positioned that when said plungers respectively are operative upon the composition cork within alternate molds, a charge of composition cork 65 will be delivered to each mold adjoining that upon which a plunger is operative, and removable means closing the bottoms of said molds, whereby said molds may progressively 70 have composition cork compacted therein, be subjected to an elevated temperature while passing through said oven, and to a cooling action while passing from said oven to said ejecting mechanism, and have the completely 75 formed composition cork slabs successively ejected therefrom after leaving said low temperature zone.

11. An apparatus for making composition cork slabs embodying therein a compacting mechanism, an oven, means whereby an elevated temperature may be maintained in said oven, an ejecting mechanism, a continuous track structure extending adjacent said compacting mechanism, through said oven and adjacent said ejecting mechanism, said ejecting mechanism being spaced away from said oven to form a low temperature zone, a carriage movable upon said track structure, a plurality of molds secured to, and movable with, said carriage, spaces between adjacent molds whereby the side walls of the molds will be reinforced and air passages between said molds are formed, and removable means closing the bottoms of said molds, whereby said molds may progressively have comp- 120

sition cork compacted therein, be subjected to an elevated temperature while passing through said oven, and to a cooling action while passing from said oven to said ejecting mechanism, and have the completely formed composition cork slabs ejected therefrom after leaving said low temperature zone.

12. An apparatus for making composition cork slabs embodying therein a compacting mechanism, an oven, means whereby an elevated temperature may be maintained in said oven, an ejecting mechanism, a continuous track structure extending adjacent said compacting mechanism, through said oven and adjacent said ejecting mechanism, said ejecting mechanism being spaced away from said oven to form a low temperature zone, a carriage movable upon said track structure, a plurality of molds secured to and movable with, said carriage, spaces between adjacent molds whereby the side walls of the molds will be reinforced and air passages between said molds are formed, a top plate common to all molds upon said carriage and having a sequence of upwardly flared openings therethrough and registering respectively with the narrow open top edges of the various mold spaces, and removable means closing the bottoms of said molds, whereby said molds may progressively have composition cork compacted therein, be subjected to an elevated temperature while passing through said oven, and to a cooling action while passing from said oven to said ejecting mechanism, and have the completely formed composition cork slabs ejected therefrom after leaving said low temperature zone.

13. An apparatus for making composition cork slabs embodying therein a compacting mechanism, an oven, means whereby an elevated temperature may be maintained in said oven, an ejecting mechanism, a continuous track structure extending adjacent said compacting mechanism, through said oven and adjacent said ejecting mechanism, said ejecting mechanism being spaced away from said oven to form a low temperature zone, a carriage movable upon said track structure, a plurality of molds secured to, and movable with, said carriage, spaces between adjacent molds whereby the side walls of the molds will be reinforced and air passages between said molds are formed, a bottom plate having spaced bars thereon, and means whereby said bars may be moved into or out of position, closing the open bottom of the various molds upon the carriage, whereby said molds may progressively have composition cork compacted therein, be subjected to an elevated temperature while passing through said oven, and to a cooling action while passing from said oven to said ejecting mechanism, and have the completely formed composition cork slabs ejected therefrom after leaving said low temperature zone.

14. An apparatus for making composition cork slabs embodying therein a compacting mechanism, an oven, means whereby an elevated temperature may be maintained in said oven, an ejecting mechanism consisting of a single reciprocatory plunger, crank wheels, connecting rods between said crank wheels and said plunger, a continuous track structure extending adjacent said compacting mechanism, through said oven and adjacent said ejecting mechanism, said ejecting mechanism being spaced away from said oven to form a low temperature zone, a carriage movable upon said track structure, a plurality of molds thereon, and removable means closing the bottoms of said molds, whereby said molds may progressively have composition cork compacted therein, be subjected to an elevated temperature while passing through said oven, and to a cooling action while passing from said oven to said ejecting mechanism, and have the completely formed composition cork slabs ejected therefrom after leaving said low temperature zone.

15. An apparatus for making composition cork slabs embodying therein a sequence of plungers of progressively decreasing, graduated lengths, means imparting reciprocatory movement to said plungers, a hopper adapted to receive composition cork, means operating in synchronism with said plungers, whereby a measured quantity of composition cork is delivered from said hopper to molds in advance of each of said plungers, an oven, means whereby an elevated temperature may be maintained in said oven, an ejecting mechanism consisting of a single reciprocatory plunger, crank wheels, connecting rods between said crank wheels and said plunger, the movement of said last named plunger being synchronized with that of said first named sequence of plungers, a continuous track structure extending adjacent said plungers, through said oven and adjacent said ejecting mechanism, said ejecting mechanism being spaced away from said oven to form a low temperature zone, a carriage movable upon said track structure, a plurality of molds thereon, said molds being so positioned that when said plungers respectively are operative upon the composition cork within alternate molds, a charge of composition cork will be delivered to each mold adjoining that upon which a plunger is operative, and removable means closing the bottoms of said molds, whereby said molds may progressively have composition cork compacted therein, be subjected to an elevated temperature while passing through said oven, and to a cooling action while passing from said oven to said ejecting mechanism, and have the completely formed composition cork slabs successively ejected therefrom after leaving said low temperature zone.

16. An apparatus for making composition cork slabs embodying therein a sequence of plungers of progressively decreasing, graduated lengths, means imparting reciprocatory movement to said plungers, a hopper adapted to receive composition cork, chutes leading therefrom in advance of each of said plungers, means actuated in synchronism with said plungers whereby a measured 5 quantity of composition cork will be delivered to each chute with each reciprocation of said plungers, an oven, means maintaining an elevated temperature therein, an ejecting mechanism comprising a reciprocatory 10 plunger, means whereby said plunger is actuated in synchronism with said first named plungers, a continuous track structure extending adjacent said first named plungers, passing through said oven and extending 15 adjacent said ejecting mechanism, said ejecting mechanism being spaced away from said oven to form a low temperature zone of the desired length, a carriage movable upon said track structure, a plurality of molds fixedly 20 mounted thereon, spacers between said molds for reinforcing the side walls thereof, affording air spaces between adjacent molds, and positioning said molds to bring the alternate molds in operative relation to said 25

first named plungers, and the intermediate 30 molds in operative relation to said chutes respectively, a top plate common to all molds upon said carriage, and having upwardly flared openings above the narrow open top of each mold, guide bars above 35 and upon opposite sides of said track structure adjacent said graduated and said ejecting plungers respectively, means carried by the molds upon each carriage respectively 40 engaging said guides, whereby the molds upon each carriage are held in alinement with the plunger or plungers adjacent said guides, and removable means closing the bottoms of said molds respectively, whereby said molds may progressively have composition cork compacted therein, be subjected 45 to an elevated temperature while passing through said oven, and to a cooling action while passing from said oven to said ejecting mechanism, and have the completely 50 formed composition cork slabs ejected therefrom after leaving said low temperature zone.

In witness whereof I have hereunto affixed my signature this 13th day of June, 55 1923.

CHARLES E. McMANUS.
